US00D545673S

(12) **United States Design Patent** (10) **Patent No.:** **US D545,673 S**
(45) **Date of Patent:** **** Jul. 3, 2007**

(54) **SLIDE LATCH**

(75) Inventors: **Jeff Antonucci**, West Chester, PA (US);
Robert Neale, Worcester (GB); **Ismael Rodriguez**, West Chester, PA (US)

(73) Assignee: **Southco, Inc.**, Concordville, PA (US)

(**) Term: **14 Years**

(21) Appl. No.: **29/217,639**

(22) Filed: **Nov. 19, 2004**

(51) **LOC (8) Cl.** **08-07**

(52) **U.S. Cl.** **D8/400**

(58) **Field of Classification Search** **D8/332, D8/333, 330, 400, 300, 313, 321, 326-331, D8/353; 292/229; 70/431**

See application file for complete search history.

CLAIM

The ornamental design for a slide latch, as shown and described.

DESCRIPTION

FIG. 1 is a top plan view of a slide latch showing our new design;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a perspective view thereof; and,

FIG. 7 is a bottom plan view thereof.

The broken lines in the figures are for illustrative purposes only and form no part of the claimed design.
